UNITED STATES PATENT OFFICE.

FRANK J. KUMMETH, OF HERON LAKE, MINNESOTA.

STRINGED MUSICAL INSTRUMENT.

Application filed November 10, 1919. Serial No. 336,834.

To all whom it may concern:

Be it known that I, FRANK J. KUMMETH, a citizen of the United States, residing at Heron Lake, in the county of Jackson, State 5 of Minnesota, have invented certain new and useful Improvements in Stringed Musical Instruments; and I do hereby declare the following to be a full, clear, and exact description of the invention, such as will 10 enable others skilled in the art to which it appertains to make and use the same.

This invention relates to a class of musical instruments and has particular reference to an improved stringed instrument 15 combining the essential characteristics of a violin and a graphophone or what may be termed a violaphone. The invention has among its particular objects, to improve the construction of instruments of this class 20 by providing a novel relation of body, horn and strings, in connection with novel means affording connection between the strings and a series of sound boxes including diaphragms.

25 Among other objects of the invention are to provide an efficient arrangement of diaphragms for transmission of the sound through the body of the instrument to a horn; to produce novel connections for 30 transmitting vibration from the strings of the instrument to the diaphragms and for supporting the strings in such a manner that the diaphragms will properly respond to them when they are bowed.

35 It is a further object of the invention to produce a stringed instrument having a tone resembling that of a brass instrument the cost of which would be much greater than the instrument of the present invention.

40 With the above objects and others in view as will appear as the specification proceeds, the invention comprises certain novel combinations and arrangements of parts as 45 will be hereinafter more particularly pointed out and claimed.

Reference is had to the accompanying drawings forming a part of this application, wherein like characters designate corresponding parts throughout the several views, in which—

Figure 1 is a side elevation of my improved musical instrument,

Figure 2 is a plan view,

55 Figure 3 is a cross sectional view taken

on the staggered section line 3—3 of Figure 2,

Figure 4 is a cross sectional view taken on the line 4—4 of Figure 2, and

Figure 5 is an enlarged detail showing 60 one of the pivot sockets of a vibrator bar.

Figure 6 is a detail perspective view of one of the vibrator bars having one end portion broken away.

Referring to the drawings in detail, the 65 improved instrument is shown as comprising a body 10 preferably of wood, the same being made of substantially triangular cross section corresponding to an equi-lateral triangle though having the apex thereof 70 truncated or depressed, as shown at 11 so as to facilitate mounting of the tail piece and strings as will be later described. The body is also provided or formed with a tapered extension 12 producing a chin and 75 shoulder rest which may be carved in a scroll or other attractive design and which is of the proper size and shape to fit the chin and shoulder as in the case of a violin or corresponding instrument. At its other 80 end, the body is provided with a longitudinal circular bore or opening 13, said body having its longer sides upwardly tapered as shown. In said bore is received a horn tube 15 which is provided with a bell 85 16 and said horn tips slightly downward so as to run nearly parallel with the finger board 17 which is mounted upon the flat face 11 at the fore end thereof and upon the horn tube adjacent to the bell is mounted a suitable peg box 18, with the pegs of which the strings of the instrument are connected for tuning.

90 Mounted upon the face 11 is a tail piece and pivot socket plate 19 preferably provided with an intermediate portion of reduced width as shown at 19', the end portion 20 thereof disposed toward the fore end of the body and the finger board, being provided with a series of equidistantly 95 spaced and transversely alined conical pivot sockets 21. The opposite end of the tail piece and plate 19 is turned or bent upon itself as shown at 22 and provided with a corresponding series of conical pivot sockets 100 23 in the bottom portion thereof, as shown in Figure 4; while the top portion is provided with a series of string openings 24 to which the adjacent ends of the strings 105 25 are anchored, the strings extending over 110

said plate and the finger board for connection to the pegs of the tuning apparatus or head 18.

5 Mounted transversely on the plate 19 is an adjustable bridge including a yoke 26 the sides of which are connected by a bridge piece 27 which is in the form of a threaded screw finely threaded on which are mounted a series of grooved nuts or 10 discs 28, one for each string and each serving to permit transverse adjustment of the string where it crosses the bridge for a purpose to be hereinafter made apparent.

In the opposed sloping sides of the body 15 10 and communicating with the bore 13 which extends from the fore end of the body and terminates in a closed wall spaced from its opposite end, there are provided a series of laterally directed openings or passages 29 20 diverging outwardly and arranged with their axes substantially at right angles to the planes of said opposed faces. These faces are recessed circularly as shown at 30 so as to receive therein a suitable disc or 25 diaphragm 31 of metal, mica or celluloid held in spaced relation to the bottom of the recess in each instance, by a rubber or like gasket 32 providing a sound space 33 preferably of a thickness of about $\frac{1}{16}$ of an inch. 30 Outwardly of the disc there is engaged a rubber or other gasket or ring 34, all of said parts being retained in position through the medium of a metallic gasket or holding ring 35 screwed or otherwise attached to the 35 body as shown at 36. As shown, the recesses are of slightly smaller diameter than the height of the sides of the body and the metal gaskets or rings 34 are also of smaller diameter than the height of the sides, the 40 holes or passages 29 being comparatively small, in fact being smaller than the diameter of the bore 13 which communicates with the space within the horn or the sound box 15.

45 Mounted longitudinally on the plate 19 are a series of spaced parallel vibrator bars 37, the same having tapered pivot projections 38 extending downwardly therefrom at each end to engage corresponding sockets 50 21, the sockets being of considerably larger diameter than the base portions of the pivots so that the pivots will contact only at the extreme points or apexes thereof, that is the points being more acute than the sockets 55 so as to allow the bars to have full freedom to vibrate without distortion of the sound waves which will be produced in the playing of the instrument as will be set forth hereinafter. Each bar is provided with an upwardly extending arm or lug 39 intermediate of its length, each lug tapering in thickness toward its upper end in the direction of the longitudinal dimension of the bar and notched as shown at 40, each to 60 receive a string 25 and to effectively retain

the string therein, it being understood that the strings may be made of wire, gut or other suitable string material. At one end of each bar there is provided an outwardly extending arm 41 from which extends laterally and downwardly a vibrator arm 42 the extremity of which is connected centrally to its respective disc or diaphragm. Each vibrator arm is disposed in a plane at right angles in the plane of the disc to which it is connected and each disc or diaphragm is disposed with its center in a plane that includes the apex of the pivot 38 of its respective bar 19 so that if a straight line is drawn across the face of the diaphragm it would fall directly across the pivot point of its respective bar. Furthermore, since in the form illustrated, four strings, four bars and four diaphragms are employed, and since the outer bars are connected to the front diaphragms and the inner bars are connected to the rear diaphragms and are therefore set inwardly further than the outer bars, the diaphragms of the rear bars must correspondingly be set at a lower incline than the front diaphragms to obtain the relation of parts specified, the arms 42 merely being offset inwardly at a greater distance in addition to the diaphragms being set in deeper with respect to the body. The purpose of this is to deliver the full force of the vibration of the bar to the diaphragm, for as shown, the lugs 39 radiate or diverge outwardly or said lugs may be said to extend downwardly and slightly inwardly from the strings at such an angle as to transmit a vibration to its respective sound disc or diaphragm. Thus, in playing the instrument as the bow is moved across the strings, the bars are vibrated so that the vibrations are transmitted directly to the axis of each diaphragm to produce the strongest and largest possible volume of sound.

It is also to be understood that the number of strings, lugs, diaphragms and related parts may be varied so as to simulate string instruments of various kinds which while played in the ordinary manner, will result in a sound being produced simulating that of a brass instrument, and a considerably greater volume than would be produced by the ordinary instrument, although played exactly like the ordinary instrument without requiring that the violinist or player of a particular instrument learn to play the special instrument. The transmission of a neutral vibration is accomplished by screwing the discs to the right or left so as to balance the pressure of the strings on their respective lugs and thus avoid any possible pressure being transmitted to the sound discs or diaphragms of the sound boxes carried by the body, which would otherwise result in decreasing the volume of sound produced. Also by having the string lugs radiating as

described, in order to obtain a neutral vibration, the bow must be drawn at right angles or perpendicularly to the string and at right angles to its lug, so that the bow will be tilted to different angles in order to clear the idle strings but will permit engagement with a plurality of strings when necessary in the playing of the instrument.

What is claimed is: —

10 1. A stringed musical instrument comprising a body having a chamber within it, a plurality of tone producing strings supported from the body, a plurality of diaphragms and means connecting each string 15 with a diaphragm for bodily vibration of the diaphragm from the bodily vibration of the string through the bodily movement of the corresponding connecting means.

2. A stringed musical instrument comprising a body having a chamber within it, a plurality of strings supported from the body, an oscillatory bar for each string having an arm upon which the string rests for oscillation of the bar in response to vibration of the string, a diaphragm for each bar carried by the body and connection between each bar and the diaphragm for vibration of the latter in response to oscillation of the bar.

30 3. The combination with a stringed musical instrument comprising a sound box provided with a diaphragm, of a string support movable in response to vibration of the string, a connection between the support and diaphragm for vibrating the latter from the support and therewith the string with respect to the diaphragm in the general direction of vibration of the diaphragm.

40 4. In a stringed musical instrument, the combination with a body and a tone producing vibratory diaphragm carried thereby, of a string support carried by the body and vibratory under influence of vibration 45 of the string, connection between the support and diaphragm for vibrating the latter in response to vibratory movement of the support and a bridge having a member with which the string is engaged, said member being adjustable in a direction transverse to the string and in response to which the string and support are adjustable in the general direction of vibration of the diaphragm.

55 5. A stringed musical instrument comprising a body having a passage within it and a series of lateral holes leading thereto; tone producing diaphragms mounted in the body over said holes, a series of oscillatory bars supported by the body, each having 60 an arm connected to a diaphragm, strings mounted over the bars and supports carried by the bars and engaged by the strings.

65 6. A stringed musical instrument comprising a body having a passage within it and a series of lateral holes leading thereto;

sound producing diaphragms mounted in the body over said holes, a series of vibrator bars pivotally supported upon the body and each having an arm connected to a diaphragm, a plate mounted on the body 70 and having a tail piece, a finger board extending from the body, a horn extending from the body, a string tensioning means on the horn, strings between the string tensioning means and the tail 75 piece over said bars, notched lugs on the bars receiving the strings, a bridge on the plate and body and having an adjusting screw traversing the bars and strings, and nuts on said screw having grooves receiving 80 the strings therein.

7. A stringed musical instrument comprising a body having a passage within it and a series of lateral holes leading thereto; sound producing diaphragms mounted in 85 the body over said holes, a plate mounted upon the body, sockets formed in spaced series in said plate, bars having pivot points movably fitting said sockets, one end of each bar having an offset arm connected centrally 90 to a corresponding diaphragm with the diaphragms in alinement with the pivot points and means on the bars for engagement by the strings of the instrument.

8. A stringed musical instrument comprising a body having a passage within and a series of lateral holes leading thereto; sound producing diaphragms mounted in the body over said holes, a plate mounted upon the body, sockets formed in spaced 100 series in said plate, bars having pivot points movably fitting said sockets, one end of each bar having an offset arm connected centrally to a sound diaphragm, notched lugs 105 projecting upwardly from the bars, strings engaging said lugs and means to adjust the tension of the strings transversely to relieve the diaphragms of pressure.

9. A stringed musical instrument comprising a cross sectionally truncated triangular body having a longitudinal passage within it communicating with one end, a sound box extending from said end in the direction of the body, a rest extending from the other end of the body, a plurality of 110 sound producing diaphragms supported at the sloping sides of the body, the body having passages within them adjacent thereto, a plurality of strings supported above the body for lateral movement and 115 rigid connections between the strings and the diaphragms to transmit motion from the strings to the diaphragms directly and at right angles to the diaphragms.

In testimony whereof, I affix my signature, in the presence of two witnesses.

FRANK J. KUMMETH.
